UNITED STATES PATENT OFFICE.

NORMAN R. SMITH, OF SEATTLE, WASHINGTON.

ROTARY ENGINE.

No. 869,147.

Specification of Letters Patent.

Patented Oct. 22, 1907.

Application filed January 25, 1906. Serial No. 297,843.

To all whom it may concern:

Be it known that I, NORMAN R. SMITH, a citizen of the United States, and resident of the city of Seattle, in the county of King and State of Washington, have invented 5 certain new and useful Improvements in Rotary Engines, of which the following is a specification.

My invention relates to an improvement in rotary engines and comprises the novel parts and combinations of parts which will be hereinafter described and 10 particularly pointed out in the claims.

The object of my invention is, in general, to improve and simplify the construction and operation of rotary engines.

One object which I have in particular is to produce 15 a rotary engine in which all of the moving parts have only a rotative motion and in which none of the parts have a reciprocating motion, thereby avoiding the loss of power due to the acceleration and retardation of reciprocating members.

20 In the drawings accompanying and forming a part of this specification I have shown my engine embodied in the form which is now preferred by me.

Figure 1 is a transverse section and partial elevation of my engine with one of the casing heads removed. 25 Fig. 2 is a section taken on a vertical plane passing through the central shaft. Fig. 3 is an elevation and partial transverse section, the line of section being through the ports or steam passages in one of the casing heads. Fig. 4 is an end elevation of the engine showing 30 only the shafts and base frame in section. Fig. 5 is a section taken just inside of the outer bearing at the end which is supplied with the connecting gears. Fig. 6 is a diagram showing an end elevation of three of the connecting rotary heads illustrating the construction 35 of the wing plate at the ends of the central or abutment head. Fig. 7 is a section on the horizontal central line of Fig. 6.

Most rotary engines have one or more parts, as for instance the abutments, which have a reciprocating motion, and for this reason the wear on the parts is very 40 much increased, additional friction is produced and increased strain is caused by the periodic necessity for retarding and accelerating these reciprocating parts. For this reason the speed of rotation is limited, and the 45 full value of the rotative feature is not utilized.

One of the chief objects in view in designing my present invention has been to entirely do away with all 50 reciprocative motion, from which it results that the speed at which the engine may run is limited to the ability of the parts to resist centrifugal strain.

My engine comprises a central rotary head about 55 which are grouped a plurality of rotary heads, all of said heads having practically the same outline, that is, consisting of peripheral surfaces such that two heads may turn and maintain constant peripheral contact, certain portions of the periphery having a greater radius than

others. In other words the rotary heads are lobed, and, in the form shown, which form is now preferred by me, the peripheral surfaces consist of circular segments which are alternately of a larger and of a smaller 60 radius. The surfaces upon co-acting heads are so proportioned that there is at all times peripheral contact between the two heads of such character as to form a substantially steam tight joint. The outlines of these heads are clearly shown in Fig. 1 which represents an 65 elevation of the engine with the casing head removed, a portion of the cylinder casing being shown in section. In this figure one of the wing plates on the central or abutment head is also removed in order to better show other parts. The position and construction of these 70 wing plates, is, however, clearly shown in Figs. 2, 6 and 7.

All of the rotary heads are of the same type. I have shown these heads as having only two lobes each. The number of lobes on each head may however be varied 75 and made only one lobe to the head or any larger number desired. Each head consists of alternate segments of a larger and a smaller diameter, said segments each extending through arcs of the same size. With a head having two lobes, these arcs will be 90°. The cross sectional shape of head preferred is clearly shown in Fig. 1.

I have shown a single central head 1 mounted upon a shaft 10, and four co-operative heads 2 which intermesh with the central abutment head 1. The segment having a larger radius on one of these heads contacts with a 80 segment of a smaller radius on another head. The four heads 2 are mounted upon shafts 20 and placed at equal distances about the central head 1 and so as to contact therewith. The various shafts extend outward where they are connected by gears 8 which intermesh and insure uniformity of rotation. 90

The central or abutment head 1 also acts as a valve, controlling the supply of steam to the outer or power heads 2. The abutment head has ports 11 extending from its end face to the periphery of the segments of the 95 larger radius. These ports are preferably located on the diameter passing through the center of said segments. The power heads 2 are of the same length as the abutment head 1, but the abutment head has an extension at each head consisting of a wing plate 12 which 100 is a complete circle in outline and which has ports 13 coextensive with ports 11 in the abutment head.

Steam is supplied through these ports, preferably from stationary ports at each end of the head. If the engine is to be non-reversible, that is, operated in one 105 direction only, the ports 53 from which the steam is received may be formed in the casing head. These ports, which are shown dotted in Fig. 1, should be so located that the steam admission to the ports 11 begins at or immediately after the time when the peripheral opening 110 of the port 11 passes the point of contact with the co-acting power head 2. The position of the heads shown

in Fig. 1 is the position occupied at the time when the beginning of this port opening occurs for two of the power heads. If the engine is to be reversible, means must be provided for shifting the location of the ports in 5 the casing head to the opposite side of the line passing through the central shaft and the outer power shafts. These ports 53 in the casing head correspond in number with the number of power heads. In order to shift the position of these ports I have placed them in a reversing disk, which disk is clearly shown in Figs. 2 and 3. This reversing disk 5 is preferably made hollow and as herein shown has a central opening through which the shaft 10 passes, thus making of the disk a hollow annulus. The annular space 50 in this disk extends entirely about the shaft and the disk has a port opening in 15 its periphery at one side, of such angular extent as at all times to connect with the steam passage 40 in the casing head 4. The extent of the port opening 51 and of the steam passage 40 is such that the shifting of a reversing disk will never close the port opening such an amount as to materially throttle the steam.

The reversing disk 5 is mounted in a cylindrical recess formed in the casing head, the disk fitting this recess as tightly as is feasible without creating undue friction when turned. The contacting surfaces are preferably secured against leakage by means of spring packing rings, as is clearly shown in Fig. 2. This reversing disk is prevented from being forced outward by means of a ring 55 which is secured to the casing head 30 by bolts and which overlaps the edge of the reversing disk so as to form a good bearing. I prefer that the walls of the recess in which the reversing disk is seated extend outward a little less than the thickness of the disk so that the force of contact of this reversing disk 35 against the wing plates in the abutment head may be adjusted so as to secure a steam tight joint without undue friction. This construction leaves a good portion of the outer surface of the reversing disk exposed and permits of the direct attachment of the reversing lever 40 54 by means of which the disk may be shifted to reverse the engine.

The period of admission of the steam is determined by the angular extent of the ports in the abutment head and in the reversing disk. This period of admission as 45 shown in the drawings and as preferred by me, lasts from the time when the center of the greater segment in the abutment head begins to leave one of the power heads, until the steam port in the abutment head reaches the corner of the casing lying between the 50 pockets or recesses occupied by two adjacent power heads. This is practically through an angle of 45°.

Steam discharge through the port in the abutment head enters the space between the periphery of said abutment head and the power head, acting upon the 55 radial space extending from the smaller to a larger radius of the larger head. This space constitutes the effective piston area. At the time when the port in the abutment head passes the corner of the casing referred to, the corner of the abutment head located 60 at the following end of the outer segment, leaves contact with the segment of the smaller radius on the power head, and at the same time the advancing corner of the segment of larger radius on the power head contacts with the advancing corner of the segment of 65 smaller radius on the abutment head, thus maintain-

ing the integrity of the joint back of the steam. From this point until the segment of larger radius has entirely cleared the corner of the casing referred to, the steam acts expansively. The action of the steam during this period of expansion is an impelling force upon 70 two of these surfaces and a retarding force upon one, thus leaving a balance of impelling force upon one of these surfaces. In the construction shown, the period of admission is through an angle of 45° in each head, and there are four heads which are successively brought 75 into action. The action, therefore, consists of a series of admissions extending over 45°, alternating with a series of expansions, each extending over 45°, thus including the entire circle. Should it occur that the engine stopped with the ports in a position occupied 80 during one of these expansion periods, or should it be desired to momentarily increase the power of the engine, it is desirable to have available means for admitting steam to the engine during the normal period of expansion. I have provided for this by means of pass-over or auxiliary valves, one of which is supplied for each power head. These pass-over or auxiliary valves are located in the casing, in the exterior angle between the pockets or cylinders occupied by the power heads. In the form shown a cylindrical seat 33 extends through 85 the casing from side to side and receives a valve consisting of a tube 6 which should fit snugly in this seat, but be free to turn. This seat is connected by means of two ports 66, with both adjacent pockets or cylinders occupied by the power heads 2. The valve 6 is 90 provided with a single port 60 which normally lies between the two ports 66 so that steam will not normally be admitted through these auxiliary valves. When, however, it is desired to utilize these valves, it is only necessary to turn them so as to bring the port 95 in the valve in registry with one of the ports in the casing, whereupon steam will be admitted to the expansion space in the cylinder and the engine may be started.

The cylinder casing 3 has a steam chest 36 cast therein 100 on its upper side and this communicates by ports 37 with the steam passages 40 in the casing heads 4 at each side, and by opening 38 with the steam supply pipe 39. Both casing heads have openings in the inner walls of the steam passages 40, registering with 105 the seat containing the pass-over valve 6. The valve 6 has side openings or ports 61 located in the steam passage 40 in one casing head, through which steam may be supplied. The other end communicates directly with the passage 40 in the opposite casing head. 110

The casing heads have steam passages 41 extending from the recess occupied by the reversing disk to and surrounding the other three pass-over valves. The details of construction above described apply to these also. Steam passages 41 connect with ports 52 in the 115 periphery of the reversing disks through which they receive their steam. These ports are also of sufficient extent, as shown in Fig. 3, to maintain connection when the reversing disk is shifted.

In one of the casing heads the seat for the pass-over 120 valves extends through the outer walls of the passages 40 and 41. This end of the valve is plugged and has a stem 62 projecting from the casing head and utilized to turn the valve. All four of these valves should be turned at the same time and in like amount. The 130

means which I have adopted for securing this consists of segment arcs 63 secured to the stems and connected by a flexible steel tape 64, a chain, links, or other like device. One of these segment arcs is provided with a handle 65 by which it may be shifted, thereby shifting all the others.

The pass-over valves are held in place against end removal by a collar 67 which bolts to the casing head. I have shown this collar as having beveled ring-like surfaces at 68 bearing respectively upon the end of the valve tube and upon the casing head, whereby a steam tight joint may be maintained.

Steam is preferably supplied at both ends of the abutment head 1, thereby avoiding the wear and friction which would be caused by unbalanced end thrust. The reversing disk, ports in casing heads etc., are therefore duplicated at each end of the engine.

As I have herein shown it, the frame and cylinder ports are provided with side lugs 71 which rest upon and are secured to longitudinal I-beams 7 which are in turn secured together by a bottom plate or bar 70 to form a bed frame. Any other form of bed frame may, however, be employed.

The cylinder casing is shown as having a peripheral exhaust channel 32 communicating with all the exhaust ports 31 and provided with openings 34 at either side and bottom adapted to receive an exhaust pipe connection. Whichever one of these is most convenient may be used, the other being stopped by a plain plate.

As the exhaust ports 31 extend substantially clear across the cylinder casing I have thought it wise to strengthen this point by peripherally extending ribs or webs 34 which overlap the ports 31.

The details of construction herein described are those which are now preferred by me and not necessarily the only practicable ones nor the only ones contemplated by me. They are therefore not to be considered as exclusive of the use of other constructions as substitutes.

What I claim is:

1. A rotary engine comprising a series of rotative heads each having peripheral segments alternately of a larger and of a smaller radius, one of said heads being placed centrally of and having peripheral contact with the others, said contact being between segments of the larger radius on one and segments of the smaller radius on the other, and means controlled by the central head for admitting steam to the chambers containing the outer heads and at points without the greater radius of the central head.

2. A rotary engine comprising a central abutment head and a plurality of power heads grouped about said central abutment head, said heads all being of like shape and comprising peripheral segments alternately of larger and smaller radius, the power heads peripherally contacting with the abutment head by a surface of the larger radius on one with a surface of the smaller radius on the other, said abutment head having inlet ports opening out in its peripheral surfaces of the larger radius.

3. A rotary engine comprising a series of rotative heads each having peripheral surfaces alternately of a larger and a smaller radius adapted to permit their turning uniformly and maintaining peripheral contact, one of said heads being placed centrally of and maintaining contact with the others, said central head being provided with ports adapted to discharge the steam centrally of its larger peripheral segments.

4. A rotary engine comprising a series of rotative heads each having peripheral surfaces alternately of a larger and a smaller radius adapted to permit their turning uniformly

and maintaining peripheral contact, one of said heads being placed centrally of and maintaining contact with the others, said central head being provided with ports extending from its end face to the peripheral segments of the larger radius, and a non-rotative member having ports for supplying steam to the ports in the central head.

5. A rotary engine comprising a series of rotative heads each having peripheral surfaces alternately of a larger and a smaller radius adapted to permit their turning uniformly and maintaining peripheral contact, one of said heads being placed centrally of and maintaining contact with the others, said central head being provided with ports extending from its end face to the peripheral segments of the larger radius, and a non-rotative member having ports equal in number and angularly disposed to correspond to the outer heads for supplying steam to the ports in the central head.

6. A rotary engine comprising a series of rotative heads each having peripheral surfaces alternately of a larger and a smaller radius adapted to permit their turning uniformly and maintaining peripheral contact, one of said heads being placed centrally of and maintaining contact with the others, said central head being provided with ports extending from its end face to the peripheral segments of the larger radius, a non-rotative member having ports for supplying steam to the ports in the central head and means for swinging said non-rotative member to opposite sides of a central position to control the direction of rotation of the heads.

7. A rotary engine comprising a series of rotary heads having lobes and circular segmental peripheral surfaces, one of said heads being centrally placed and the other intermeshing therewith with peripheral contact, said central head having steam supply ports discharging centrally of the periphery of its lobes and receiving their supply from the end face of the head, a reversing disk engaging said end face and having ports therein adapted to register with the ports in the end face of the rotary head, and means for shifting the angular position of said reversing disk.

8. A rotary engine comprising a series of lobed rotary heads, one of said heads being placed centrally and the others intermeshing therewith, said central head having circular disks at its ends overlapping the end faces of the other heads.

9. A rotary engine comprising a series of lobed rotary heads, one of said heads being placed centrally and the others intermeshing therewith, said central head having circular disks at its ends overlapping the end faces of the other heads and also having steam supply ports extending from its end face inward.

10. A rotary engine comprising a series of lobed rotary heads, one of said heads being placed centrally and the others intermeshing therewith, said central head having circular disks at its ends overlapping the end faces of the other heads and also having steam supply ports extending from its end face to the outer periphery of the lobe.

11. A rotary engine comprising a series of lobed heads, one of said heads being placed centrally and the others intermeshing therewith, said central head having circular disks at its ends overlapping the end faces of the other heads and also having steam supply ports extending from its end face inward, a reversing disk engaging said end face and having ports adapted to register with the ports in the said head and means for angularly shifting said reversing disk.

12. A rotary engine comprising a series of rotary heads each having peripheral segments alternately of a larger and of a smaller radius, one of said heads being placed centrally of and having rotative peripheral contact with the others, said central head having circular end disks overlapping the end faces of the other heads, said central head also having the steam supply ports extending from its end faces inward and the other heads being without ports.

13. A rotary engine comprising a series of rotary heads each having peripheral segments alternately of a larger and of a smaller radius, one of said heads being placed centrally of and having rotative peripheral contact with the others, said central head having circular end disks overlapping the end faces of the other heads, said central head also having the steam supply ports extending from its end

- faces inward and the other heads being without ports, reversing disks in contact with the end faces of the central head and provided with ports adapted to register with the ports in the central head, and means for shifting said reversing disks to place their ports at either side of a central position. 5
14. A rotary engine comprising a rotary piston head having supply ports in its end face, a normally stationary hollow disk having a peripheral supply port and side discharge ports therein adapted to register with the ports in the rotary head, and means for reversing the engine by turning said reversing disks. 10
15. A rotary engine comprising a lobed rotary head having circular end disks of a radius equal to the maximum radius of the lobes, and other lobed heads fitting and turning between said circular end disks. 15
16. A rotary engine comprising a lobed rotary head having peripheral surfaces of a larger and of a smaller radius and ports opening in its end faces beyond its smaller radius, and circular end disks secured to said head and extending beyond said ports. 20
17. A rotary engine comprising a lobed rotary head having peripheral surfaces of a larger and of a smaller radius and ports extending from its end faces at points beyond the smaller radius, circular end disks secured to said head and extending outwardly beyond said ports, reversing disks contacting with said end faces and having ports adapted to register with the ports in the heads, and means for shifting the reversing disks to alter the angular position of its ports. 25
18. A rotary engine comprising a series of lobed rotary heads having circular segmental peripheral surfaces alternately of a larger and of a smaller radius, one of said heads being centrally placed and acting as an abutment for the others, said other heads being grouped about and turning in contact with said central abutment head, said central head having the supply ports extending from its end faces and supplying steam in succession for the outer heads, a cylinder casing having cylindrical pockets for said heads and an exhaust port for each of the outer pockets located at the side opposite to the central head. 30
19. A rotary engine comprising a series of lobed rotary heads having circular segmental peripheral surfaces alternately of a larger and of a smaller radius, one of said heads being centrally placed and acting as an abutment for the others, said other heads being grouped about and turning in contact with said central abutment head, said central head having the supply ports extending from its end faces and supplying steam in succession for the outer heads, a cylinder casing having cylindrical pockets for said heads and an exhaust port for each of the outer pockets located at the side opposite to the central head, reversing disks contacting with the central head and having ports adapted to register with the ports in said head, and means for shifting the angular position of said reversing disks to thereby control the direction of rotation of the engine. 35
20. A rotary engine comprising a central rotative head and a plurality of similar heads grouped about said central head and turning in unison therewith, said central head having within itself the steam distributing ports and acting as a valve and abutment for the other heads. 40
21. A rotary engine comprising a central rotative head and a plurality of similar heads grouped about said central head and turning in unison therewith, said central head having within itself the steam distributing ports connecting with its end face and acting as a valve and abutment for the other heads, a movable disk contacting with said end face and having ports adapted to register with the ports in the head, and means for angularly shifting said disk. 45
22. A rotary engine comprising a series of rotative heads, each having peripheral segments alternately of a larger and of a smaller radius, one of said heads being placed centrally of and having peripheral contact with the others, said contact being between surfaces of the smaller radius on one and surfaces of the larger radius on the other, said central head alone being supplied with ports which distribute steam for the other heads. 50
23. A rotary engine comprising a series of rotative heads, each having peripheral segments alternately of a 75
- larger and of a smaller radius, one of said heads being placed centrally of and having peripheral contact with the others, said contact being between surfaces of the smaller radius on one and surfaces of the larger radius on the other, said central head being supplied with ports which 85 distribute steam for the other heads, a casing inclosing said heads and having an exhaust port for each of the outer or power heads on the side opposite the central head, and supply ports at the end face of the central head. 90
24. A reversing disk for rotary engines comprising a hollow disk having discharge ports in one side face and a receiving port in its periphery. 95
25. In a rotary engine, in combination, a rotary head having ports in its end face, a normally stationary reversing disk comprising a hollow annulus surrounding the shaft and having discharge ports in one side face and a receiving port in its periphery and means for angularly shifting said disk, to reverse the engine. 100
26. A reversing disk for rotary engines comprising a hollow disk having discharge ports in one side face and a receiving port in its periphery a casing having a circular opening adapted to receive and permit turning of said disk therein with substantially a steam tight peripheral joint, said casing having a steam supply port adapted to register with the peripheral port in the disk. 105
27. A reversing disk for rotary engines comprising a hollow disk having discharge ports in one side face and a receiving port in its periphery, a cylindrical casing receiving said disk and opening externally at its outer end means for holding said disk in said casing, and a shifting lever 110 provided with connections with said disk. 110
28. A rotary engine comprising a rotative head having supply ports opening in one end face, a hollow disk contacting with said end faces and having ports adapted to register with the ports in said head, a casing having a circular recess adapted to receive said disk and form a tight peripheral joint therewith, said disk and the wall of its receiving recess having ports adapted to maintain constant registry, means for holding said disk in place and in contact with the rotative head, and a lever connected with said disk whereby it may be shifted in angular position. 115
29. A rotary engine comprising a rotary head having ports in its end face, a casing having a circular opening extending to said face of the rotary head, a hollow disk making a steam tight joint in said openings and contacting with the port surface of the rotary head, said disk having ports in its side face adapted to register with the ports in the rotary head, said disk and the wall of its receiving recess having peripheral supply ports adapted to register, a ring secured to the casing and engaging the outer surface of the disk to hold it in engagement with the rotary head, and a shifting lever secured to the disk whereby it may be shifted in angular position. 120
30. A reversing disk for rotary engines having a peripheral supply port, and discharge ports both in its periphery and side face. 125
31. A reversing disk for rotary engines having a peripheral supply port, and discharge ports both in its periphery and side face, and a fixed casing having a recess receiving said disk and making a steam tight joint with its periphery, said casing having a supply port registering with the supply port of the disk and distributing ports registering with the peripheral discharge ports of the disk. 130
32. A reversing disk for rotary engines having a peripheral supply port, and discharge ports both in its periphery and side face, and a fixed casing having a recess receiving said disk and making a steam tight joint with its periphery, said casing having a supply port registering with the supply port of the disk and distributing ports registering with the peripheral discharge ports of the disk, and means for angularly shifting said disk without disturbing its port connections with its casing. 135
33. A rotary engine comprising a series of rotary heads having intermeshing lobes adapted to turn in mutual peripheral contact, one of said heads being centrally placed and the others grouped about and peripherally contacting with the central head, a casing peripherally inclosing said rotary heads, casing heads inclosing the ends of the rotary heads, the central rotary head having steam distributing ports connecting with its end faces, hollow reversing disks 140
- 145
- 150
- 155
- 160

- contacting with the end faces of the central rotary head and having discharge ports adapted to register with the ports in the said head, the casing heads having cylindrical recesses receiving said reversing disks, said disks and 5 casing heads having peripherally registering steam ports, and means for turning said disks. 85
34. A rotary engine comprising a central rotary head and a plurality of similar rotary heads grouped about and turning with said central head, said heads having circular peripheral segments of different radii, a casing peripherally embracing said rotary heads, casing heads, said central rotary head and the casing heads having ports adapted to register at suitable times and to cut off the steam to secure expansion, a pass-over or auxiliary valve located in 10 each outer angle between the outer heads, and ports from said auxiliary valves to the adjacent cylinders, whereby steam may be supplied after it has been cut off by the central rotary head. 90
35. A rotary engine comprising a central rotary head 20 and a plurality of similar rotary heads grouped about said central head and turning in unison therewith, said heads having circular peripheral segments alternately of different radii, a casing and casing heads inclosing said rotary heads, means for controlling the normal admission of steam by the central head to secure an expansion, pass-over or auxiliary valves located in the exterior angles between the outer heads, and means for operating said auxiliary valves to admit steam to the cylinder spaces after it has been cut off by the central head. 100
36. A rotary engine comprising a central rotary head and a plurality of similar rotary heads grouped about said central head and turning in unison therewith, said heads having circular peripheral segments alternately of different radii, a casing and casing heads inclosing said rotary heads, means for controlling the normal admission of steam by the central head to secure an expansion, pass-over or auxiliary valves located in the exterior angles between the outer heads and extending from casing heads to casing head, the casing heads having supply ports connecting with both ends of the auxiliary valves, and means for operating all of said auxiliary valves together. 105
37. A rotary engine comprising a central rotary head and a plurality of similar rotary heads grouped about said central head and turning in unison therewith, said heads having circular peripheral segments alternately of different radii, a casing and casing heads inclosing said rotary heads, means for controlling the normal admission of steam by the central head to secure an expansion, a pass-over or auxiliary valve for each power cylinder and means 40 for operating said valves to admit steam to the cylinder spaces after it has been cut off by the central head. 110
38. A rotary engine comprising a central rotary head and a plurality of similar rotary heads grouped about said central head and turning in unison therewith, said heads having circular peripheral segments alternately of different radii, a casing and casing heads inclosing said rotary heads, means for controlling the normal admission of steam by the central head to secure an expansion, a pass-over or auxiliary valve for each power cylinder and means 45 for operating said valves to admit steam to the cylinder spaces after it has been cut off by the central head, said pass-over valves having stems extending to the exterior, a segment arc on each stem and flexible members connecting said segment arcs whereby all the auxiliary valves are 50 moved together. 115
39. A rotary engine comprising a central rotary head, a plurality of similar rotary heads grouped about said central head and turning in unison therewith, said heads having circular peripheral segments alternately of a larger 55 and a smaller radius a casing cylinder peripherally inclosing said rotary heads, casing heads secured to and inclosing the ends of said cylinder, means for controlling the steam admission through and by the central rotary head, the casing cylinder having a peripherally extending 60 exhaust passage or chamber and exhaust ports communicating between said chamber and each of the power chambers. 120
40. A rotary engine comprising a central rotary head, a plurality of similar rotary heads grouped about said central head and turning in unison therewith, said heads having circular peripheral segments alternately of a larger 65 and a smaller radius, a casing cylinder peripherally inclosing said rotary heads, casing heads secured to and inclosing the ends of said cylinder, means for controlling the steam admission through and by the central rotary head, the casing cylinder having a peripherally extending 70 exhaust passage or chamber and exhaust ports communicating between said chamber and each of the power chambers. 125
41. A rotary engine comprising rotary power heads and a rotary abutment head, means for controlling the distribution of steam by the abutment head, a reversing disk, said reversing disk and abutment head having co-operative 75 ports, and means whereby shifting the reversing disk will produce a reversal of the engine. 130
42. A rotary engine comprising rotary power heads and a rotary abutment head, means for controlling the distribution of steam by the abutment head, a hollow reversing disk, said disk and the abutment head having co-operative ports, a fixed member having a circular recess receiving said disk and forming a steam tight joint with the periphery thereof, said fixed member and the disk having ports maintaining registry as the disk is rocked, and means 80 whereby angular shifting of said disk and its ports causes a reversal of the engine. 135
43. A rotary engine comprising rotary power heads and a rotary abutment head, means for controlling the distribution of steam by the abutment head, a hollow reversing disk, said disk and abutment head having co-operative ports, means whereby said disk may be angularly shifted without affecting its steam supply, and means whereby such shifting produces a reversal of the engine. 140
44. A rotary head comprising a central rotary abutment head and a plurality of rotary power heads grouped about said central abutment head, said heads having circular peripheral segments alternately of different radii and adapted to turn in peripheral contact with the abutment head, said abutment head having steam ports opening in its end face and in the peripheral segments of larger radius, said ports being located on the central diameter of the segments of larger radius, a reversing disk having ports co-operative with the ports in the end face of the abutment head, and means for angularly shifting said disk to cause its ports to begin registry with those in the rotary head when the ports in the latter reach positions in line with the axes of the power heads when turning in either direction. 145
45. A rotary engine comprising a central rotary abutment head, a plurality of power heads grouped about said abutment head, said heads having circular peripheral segments of different radii and peripherally contacting with the abutment head, means for controlling the normal admission of steam by said abutment head to secure expansion in the steam cylinders, a cylinder casing having cylindrical pockets each inclosing one of said heads, said casing having cylindrical seats for pass-over or auxiliary valves located in the exterior angle between adjacent pockets and ports connecting said seats with each adjacent pocket, a tubular valve in each of said seats having a port adapted to communicate with either of its seat ports, stems for said valves extending to the exterior, and steam passages in the casing heads communicating with said valves. 150
46. A rotary engine having a lobed rotary head provided with ports in the end face of the lobes at a greater radius than the bottom of the valley between lobes, and a circular web at the end having registering ports and extending to a greater radius than the said ports. 155
47. A rotary engine having a lobed rotary head provided with ports in the end face of the lobes at a greater radius than the least radius of the valley between the lobes, and having a web continuing the said end face between the lobes and having a greater radius than said ports. 160
48. A rotary engine comprising a series of rotative heads, each having peripheral segments alternately of a larger and of a smaller radius, one of said heads being placed centrally of and having peripheral contact with the others, said contact being between segments of the larger radius on one and segments of the smaller radius on the

- other, means controlled by the central head for admitting steam to the chambers containing the outer heads at points without the greater radius of the central head, and intermeshing gears, each connected with its respective rotary head, whereby unison of rotation is secured. 5
49. A rotary engine comprising a series of rotative heads each having peripheral surfaces alternately of a larger and of a smaller radius adapted to permit their turning synchronously and maintaining peripheral contact, and intermeshing gears connected, each with its respective rotative head, the central head being provided with ports receiving steam at its end faces and discharging at its peripheries of the larger radius. 10
50. A rotary engine comprising a series of lobed rotary heads, one of said heads being centrally placed and the others intermeshing therewith, said central head having circular disks at its ends overlapping the end faces of the other heads and gears connecting said heads to insure synchronism of rotation. 15
51. A rotary engine comprising a series of lobed rotary heads, one of said heads being centrally placed and the others intermeshing therewith, said central head having circular disks at its ends overlapping the end faces of the other heads and also having steam ports extending from 20 its periphery to both end faces, the port openings in said end faces being equal in area and registering with their supply ports at the same time, whereby the end thrust of the steam is balanced. 25
52. A rotary engine comprising a series of lobed rotary heads, one of said heads being centrally placed and the others intermeshing therewith, gears connected, each with its respective rotary head and intermeshing to secure synchronous rotation, said central head having steam supply ports extending from each end face to its periphery, the opposite end face openings of said ports being of equal area whereby the end thrust of steam is balanced. 30
53. A rotary engine comprising a series of lobed rotary heads, one of said heads being centrally placed and the others intermeshing therewith, gears connected, each with its respective rotary head and intermeshing to secure synchronous rotation, said central head having a circular disk at each end overlapping the end faces of the other heads and having supply ports of equal area in each end face. 40
54. A rotary engine comprising a series of lobed rotary heads, one of said heads being placed centrally of and intermeshing with the others, means for securing synchro- 45
- nous turning of said heads, and means directly controlled by said abutment head for simultaneously admitting steam to opposite of the outer power heads, whereby the rotative effect communicated to the central shaft is balanced. 50
55. A rotary engine comprising a series of lobed rotary heads, one of said heads being centrally placed and the other heads being placed in pairs of which the heads are respectively at opposite sides of the central head and maintain an intermeshing peripheral contact therewith, means connecting said heads to insure synchronous rotation, and means controlled by one of said heads for admitting steam simultaneously to opposite heads of each pair whereby the rotative effect upon the central head is balanced. 55
56. A rotary engine comprising a series of lobed rotary heads, one of said heads being centrally placed and intermeshing with the others, a corresponding series of intermeshing gears connected, each with its respective rotary head, and means controlled by the rotation of the heads for admitting steam simultaneously to opposite outer heads whereby the rotative effect upon the central head is balanced. 60
57. A rotary engine comprising a central rotary abutment head having supply ports therein and rotary power heads turning with and grouped about the abutment head, and means for controlling the steam admission to opposite power heads to balance the steam thrust against the abutment head. 70
58. A rotary engine comprising a lobed abutment head, a plurality of power heads of the same outline as the abutment head, each meshing with said abutment head, steam admission device controlled by the abutment head and steam exhaust means controlled by the power heads. 75
59. A rotary engine comprising a central abutment head having peripheral circular arcs of different radii and power heads of like kind meshing each with the abutment head to turn in peripheral contact therewith and means controlled by the abutment head for admitting steam to the outer power heads. 80
- In testimony whereof, I have hereunto affixed my signature this 18th day of January 1906, in the presence of two witnesses.
- NORMAN R. SMITH.
